CLAIM

The ornamental design for a female urinary collection aid, as shown and described.

DESCRIPTION

FIG. 1 is a perspective view of a female urinary collection aid and showing my new design;

FIG. 2 is a side elevational view, the opposite side being a mirror image thereof;

FIG. 3 is a top plan view thereof, taken in the direction of the arrows shown along line 3—3 of FIG. 2;

FIG. 4 is a front elevational view thereof, taken in the direction of the arrows shown along line 4—4 of FIG. 2;

FIG. 5 is a rear elevation view thereof, taken in the direction of the arrows shown along line 5—5 of FIG. 2; and;

FIG. 6 is a bottom plan view thereof, taken in the direction of the arrows shown along line 6—6 of FIG. 2.

The broken line showing is for illustrative purposes only and forms no part of the claimed design.
